MINE CAR BEARING

Filed Aug. 12, 1931

Inventor

JOHN P. MILLER,

By Shepherd Canfield

Attorney's

UNITED STATES PATENT OFFICE

JOHN P. MILLER, OF DURYEA, PENNSYLVANIA

MINE CAR BEARING

Application filed August 12, 1931. Serial No. 556,700.

This invention relates to bearing boxes and more particularly to the bearing boxes of mine cars, and it has for its object the provision of an improved type of boxing of a structure which, while economical, will be much more efficient and safer in use than the boxes now used.

A further object of the invention is the provision of a boxing of the character described which will be highly efficient from the standpoint of lubrication.

A great deal of trouble and expense is caused by the bearing boxes at present in use in mine cars. Most of those at present employed comprise a pair of mere semi-circular bearing halves held in place with cotter pins. These frequently become loose and drop out permitting the wheels to become disengaged from the mine cars, frequently derailing the latter. This derailment often takes place in portions of the mine where the head room is not sufficient for the car to be lifted to replace the wheels with the result that the car has to be dragged to a point where it can be lifted.

It is therefore a primary object of the invention to provide a bearing of very rugged construction comprising a receiving housing and a pair of bearing halves, the latter being interlocked with each other and with the housing in such manner as to absolutely prevent any disengagement of the bearing halves from the housing or any disengagement of the axle from the bearing halves.

In the accompanying drawing

Figure 1 is a vertical longitudinal sectional view of a bearing constructed in accordance with the invention.

Fig. 2 is a front elevation of the complete bearing.

Fig. 3 is a front elevation of the housing with the bearing halves removed and

Fig. 4 is a rear elevation.

Like numerals designate corresponding parts in all the figures of the drawing.

Referring to the drawing 5 designates a mine car axle and 6 the hub of a mine car wheel. This hub is located between a collar 7 that is pinned to the axle 8, and the inner faces of the upper and lower bearing halves 9 and 10, respectively. These bearing halves are received within a preferably integral box

like housing 11, the top 12 of which supports a longitudinal sill 13 to which the housing 11 is secured by bolts 14. The lower bearing half 10 comprises a semi-circular bearing portion 10a which projects outwardly beyond the vertical front face of the bearing and into an annular recess 15 of the wheel hub.

The lower bearing half is continued into the housing 11 beyond the bearing portion 10a to form a box like portion 10b comprising the side walls 10c and rear wall 10d. This box like element is adapted to receive oil impregnated waste 16 and to act as an oil reservoir. It is preferably provided with barbs 17 to hold the waste in place. The bottom of the box like portion lies below the level of the bearing portion 10a with the result that a stop shoulder 10f is formed upon the lower bearing half and this stop shoulder is adapted to engage behind an upwardly extending transverse lip 10g of the housing 11.

It will consequently be observed that this locks the lower bearing half with respect to the housing. In addition, the rear wall of the housing 11 is thickened through its upper portion to form an overhanging ledge 11a beneath which the rear wall 10e of the lower bearing half engages. In putting this lower bearing half in place, the rear wall 10e is first engaged beneath the ledge 11a and then the stop 10f is moved downwardly to lie behind lip 10g. It is to be noted that the top of the rear wall 10e lies at a slightly lower level (see Fig. 1) than the tops of the side wall 10c and this permits the rear ends 85 of these side walls to engage in notches 11b formed at the terminal of the overhanging ledge 11a.

The upper bearing half 9 conforms in curvature to the axle 5 upon its under face and when slipped into place its rear end bears against the rear wall of the housing and a lip 9a of said upper bearing half lies against the recessed forward edge 12a of the top 12 of the housing and beneath a rail 11c of said housing, the sill 13 being cut out for the reception of said rail.

It is apparent that the presence of the upper bearing half 9 locks the lower bearing half against any such upward movement as

would tend to free the stop shoulder 10f from the lip 10g and since the bearing half 9 can not move outwardly because of the presence of the wheel hub 6 it follows that when the parts are once assembled it will be absolutely impossible for them to become accidentally disengaged. An oil receiving opening 18 is formed through the upper thickened portion of the rear wall of the housing 11 and its inner end overlies the box 10b in such manner that oil introduced into said opening 18 will be delivered into the oil receiving box of the lower bearing half.

The oil which travels outwardly along the semi-circular bearing portion 10a of the lower bearing half is delivered into the recess 15 from which it is conducted into an oil reservoir 6a through ports 6b whereby efficient lubrication of both axle and wheel is assured.

It will be apparent that the wheel may turn upon the axle or that the axle may turn in the bearing halves, or both. It is to be observed that the entrance to the oil receiving opening 18 is beneath the overhanging ledge 12a of the top 12 and thus the entry of dirt, coal dust, etc. to the oil compartment is prevented.

The device of the present invention will save thousands of dollars annually in the loss of time and equipment and may prevent serious accidents. It is to be understood that the invention is not limited to the precise construction set forth, but that it includes within its purview whatever changes fairly come within either the terms or the spirit of the appended claims.

Having described my invention, what I claim is:

1. The combination with a housing having a rectangular box like interior, of a pair of bearing halves adapted to fit snugly therein and provided with semi-circular inner faces for the reception of an axle, the lowermost of said bearing halves comprising a bearing portion and an inner box like portion for the reception of a lubricant, means carried by said lower half for preventing outward movement of said lower half with respect to the housing, and interlocking means between the housing and the lower bearing half for preventing upward movement of the outer end of said lower bearing half with respect to the housing, the lower edges of the upper bearing half engaging the upper edges of the lower bearing half whereby the presence of the upper bearing half prevents upward movement of the lower bearing half.

2. The combination with a housing comprising a rectangular box like interior having a rear wall that is thickened at its upper portion to provide an overhanging ledge, an oil conduit formed through said overhanging ledge, upper and lower bearing halves, the lower bearing half being provided with a bearing portion projecting outwardly beyond

the face of the housing and being extended into the housing to form a box like lubricant receiving element, the rear wall of which engages beneath said overhanging ledge, an axle received within said bearing halves, and a wheel upon said axle having a recess within which the projecting bearing portion of the lower bearing half is received.

3. The combination with a housing comprising a rectangular box like interior having a rear wall that is thickened at its upper portion to provide an overhanging ledge, an oil conduit formed through said overhanging ledge, upper and lower bearing halves, the lower bearing half being provided with a bearing portion projecting outwardly beyond the face of the housing and being extended into the housing to form a box like lubricant receiving element, the rear wall of which engages beneath said overhanging ledge, an axle received within said bearing halves, a wheel upon said axle having a recess within which the projecting bearing portion of the lower bearing half is recessed, the outer faces of the upper bearing half lying flush with the outer face of the housing and being of such shape as to directly engage and lock the lower bearing half against vertical movement.

4. The combination with a housing comprising a rectangular box like interior, of a pair of bearing halves adapted to fit snugly therein and provided with semi-circular inner faces for the reception of an axle, the lowermost of said bearing halves comprising a bearing portion which projects outwardly beyond the front wall of the housing, and a box like receptacle toward the inner end of the housing, the outer face of the upper bearing half lying flush with the outer face of the housing and said bearing halves being so shaped that they mutually interlock and hold each other in place even in the absence of the axle with which they are used, an axle adapted to be received within said bearing halves, and a wheel mounted to turn upon said axle, said wheel having a facial recess within which the projecting bearing portion of the lower half is received, the hub of the wheel bearing upon the front face of the housing to prevent outward movement of said wheel, and said hub bearing against the front face of the upper bearing half to prevent movement of said half out of said housing.

5. The combination with a housing having a rectangular box like interior, of a pair of bearing halves, the contour of the outer faces of which substantially conform to and fit within said housing, said bearing halves being provided with substantially semi-circular faces for the reception of an axle, the lowermost of said bearing halves comprising said semi-circular bearing portion and a box like depressed portion outwardly of said bearing portion for the reception of lubricant, a por-

tion of the housing lying inwardly of a portion of the lower bearing half to prevent movement of the lower bearing half out of said housing, said upper and lower bearing halves abutting each other at their meeting edges to prevent movement of said bearing halves toward each other, an axle, a wheel upon said axle having a portion lying close enough to the end face of the upper bearing half to prevent movement of said upper bearing half out of the housing, said axle being of uniform diameter outwardly of said wheel to permit of its endwise introduction between said bearing halves, and said axle being of a length to extend beyond the bearing portion of the lower bearing half and into the lubricant receptacle.

In testimony whereof I affix my signature.
JOHN P. MILLER.
